UNITED STATES PATENT OFFICE.

THOMAS KENNAN, OF BIRMINGHAM, ALABAMA.

PROCESS FOR THE SEALING OF CRACKS IN THE LINING OF BLAST FURNACES AND THE LIKE.

1,423,332.

Specification of Letters Patent.

Patented July 18, 1922.

Application filed January 14, 1922. Serial No. 529,340.

To all whom it may concern:

Be it known that I, THOMAS KENNAN, a citizen of the United States of America, residing at Birmingham, in the county of 5 Jefferson and State of Alabama, have invented certain new and useful Improvements in Process for the Sealing of Cracks in the Lining of Blast Furnaces and the like, of which the following is a specification.

This invention relates to a process for the sealing of cracks in the lining of blast furnaces and the like, and has for its object to enable the blast furnace operator to 15 seal or close up cracks in the furnace lining without having to shut down and reline the furnace.

Due to the uneven expansion and contraction between the lining and shell of the 20 furnace and to other causes, cracks from time to time occur in the lining of blast furnaces and heretofore the practice has been to shut down the furnace and reline it. Many processes have been tried experimentally to seal or close these cracks without shutting down the furnace or relining it, but so far as I am advised none heretofore have proven practical and successful.

According to the practice of my process, 30 which I will now describe in manner and form sufficiently clear for those skilled in the art to practice it, when a crack occurs in the furnace lining it is indicated by the metallic jacket opposite the crack becoming red hot and when this occurs I am able to locate and define the extent of the crack. If this occurs in the lining above the bosh and below the down-comer pipe, my process will correct it, but if occurring above the 40 bottom level of the down-comer my process will not correct it.

Assuming that a crack has occurred within the zone first described of the furnace lining, I provide as follows. First I prefer 45 to tap out of the furnace all of the molten iron and slag, but this is not essential except to protect the grade of the molten iron. I then, if such step is necessary, introduce stock sufficient to bring the stock line well 50 above the level of the crack. The blast is then cut off and one or more tuyères in vertical alignment with the zone of the crack are removed. I preferably then close off all of the other tuyères so that air can 55 gain admission to the furnace only through

the tuyère ports under the crack. By this means I cause air drawn in by the natural draft of the furnace to flow in through the open tuyère port or ports and to creep up along the furnace lining and passing over 60 the zone of the crack. This being the only air admitted to the furnace and this air flowing up between the cracked wall and the stock will result in a rapid melting of 65 the stock opposite and above the cracked zone and as this melted stock flows down the furnace lining and over the crack it will enter the latter responsive to capillary attraction and will fill and seal the crack. By raising and lowering the bell the intensity of the draft can be controlled and all of the metallic parts of the furnace properly protected.

The removal of the tuyères under the 75 crack is the simplest way of concentrating the flow of air so that it will pass up along the lining over the cracked zone, as when the tuyères are left in place with the blast on they will tend to direct the air towards the center of the furnace and to keep it 80 away from the lining.

The principle underlying my invention is to so control and direct the air that it will cause the melting of the stock opposite and above the cracked zone, and obviously 85 my invention in its simplest form is carried out when this melting is localized opposite the zone of the crack, as by localizing it I increase the intensity of the draft for the more effective melting of the stock in the 90 zone desired.

While I have described above, as a preferred method for accomplishing this, the opening of the tuyère ports under the crack and the shutting off of the blast through 95 the other tuyères, nevertheless, under certain conditions, approximately the same effect can be obtained where the blast is shut off from the tuyères under the cracked zone and is left on in one or more tuyères diametrically opposite to the cracked zone, as 100 in this way the open tuyères may be able to direct the air across the bosh and cause it to flow up along the opposite wall and over the cracked zone. Also, as a modification of my method, all of the tuyères can be removed and the bell lowered, thereby increasing the draft of air flowing up along the lining on all sides and melting down the stock all around and continuing this until 110

the crack is sealed. Obviously, quicker and better results are obtained where the draft is concentrated on the stock opposite the cracked zone.

5 In the accompanying drawing I have illustrated a typical blast furnace showing my preferred process in use. Here the furnace comprises an outer metallic jacket 1, a lining 2, a bosh 3, tuyère ports 4 for 10 tuyères not shown which are connected to the bustle pipe 5. The down-comer pipe 6 leads from the top of the furnace adjacent to the bell 7. I show a crack 8 in the furnace lining and the stock 9 is represented 15 at a level above the crack. The tuyère ports in vertical alignment with the crack are shown open and plugs 10 are shown inserted in the other tuyère ports. I show by arrows the inflow of air and it will be 20 seen passing up along the lining and over the cracked zone. This will cause a rapid melting of the stock which will flow down the furnace and over the cracked zone and will seal the crack without requiring the 25 furnace to be shut down.

Having thus described my invention, what I claim as new and desire to secure by Letters Patent, is:—

1. The hereindescribed process for the 30 sealing of cracks in the lining of blast furnaces and the like, which consists in raising the stock level above the cracked zone and concentrating a flow of air through the stock adjacent to and above the cracked 35 zone to cause the same to melt and run down the furnace lining and enter the crack.

2. The hereindescribed process for the

sealing of cracks in the lining of blast furnaces and the like, which consists in shutting off the blast, raising the stock level 40 when necessary above the cracked zone, removing one or more tuyères in vertical alignment with the cracked zone, and preventing the access of air through the other tuyères so as to cause a draft to flow through 45 the open tuyère ports up along the furnace lining and over the cracked zone.

3. The hereindescribed process for the sealing of cracks in the lining of blast furnaces, which consists in the raising when 50 necessary of the stock level above the cracked zone, and the arranging of the air admission elements so as to cause the air entering the bosh to flow up along the lining of the furnace and to melt down the 55 stock contiguous to the lining so that it will tend to flow down the lining and enter the crack.

4. The hereindescribed process for the sealing of cracks in the lining of blast furnaces, which consists in the raising when 60 necessary of the stock level above the cracked zone, and the arranging of the air admission elements so as to cause the air entering the bosh to flow up along the lining 65 of the furnace and to melt down the stock contiguous to the lining so that it will tend to flow down the lining and enter the crack, and controlling the draft by the raising and lowering of the bell. 70

In testimony whereof I affix my signature.
THOMAS KENNAN.
